UNITED STATES PATENT OFFICE

DAVID S. FAULKNER AND EDWARD TIMBS, OF LOS ANGELES, CALIFORNIA, ASSIGNEES
TO THE NATIONAL SUPPLY COMPANY OF DELAWARE, OF NEW YORK, N. Y., A COR-
PORATION OF DELAWARE

ROTARY DRAWWORKS

Application filed June 21, 1926. Serial No. 117,322.

This invention relates to a rotary drawworks such as is employed in the rotary process of drilling wells.

The principal object of this invention is to provide a rotary drawworks in which the distance between the drawworks post is maintained at a minimum and which drawworks includes a drum of relatively large size, and which drum is constructed of a spool having integral flanges and hub portions and to which spool forged brake rims are secured.

Another object of this invention is to provide a three speed rotary drawworks in which the rotary drum is preferably adapted to be rigidly secured to the drum shaft, and which drum is constructed of a spool having rolled forged brake rims secured thereto and upon which brake rims brake bands of novel construction are positioned and held equally spaced or positioned upon the said brake rims by means of cables secured to the rotary drawworks beam and to the floor of the well derrick.

Another object of this invention is to provide a three speed rotary drawworks in which clutches are provided for releasably clutching the speed sprockets to the drum shaft and in which drawworks construction, novel control means are provided for the actuation and control of the said clutches.

Another object of this invention is to provide a forged brake rim which is forged and rolled so as to insure great strength and long wear, together with the ability of such forged brake rim to afford a maximum smooth braking action.

Another object of this invention is to provide rolled forged brake rims for rotary drawworks, which rolled forged brake rims are not limited in their construction to the employment of low carbon steel and which may be made from a grade of steel especially suited to the working conditions of the brake, thereby guaranteeing the maximum strength and wearing qualities for such a brake rim.

Another object of this invention is to provide rolled forged brake rims for a rotary draw works which insures the highest maximum brake contact as well as brake power in all positions of the brake wheel with addi-

tional safety over other types of brake rims now on the market and to provide a brake rim which gives a true and smooth braking surface so as to avoid jerkiness in control.

Another object of this invention is to provide a rotary draw works drum construction in which means are provided for securing the cable which is wound upon the drum firmly in position to the brake flange so as to avoid the possibility of breaking the line loose from the drum and wear upon the end of the line where the same is secured.

Other objects and advantages of this invention will be apparent from the following detailed description of a preferred embodiment thereof, as illustrated in the accompanying drawings, in which drawings:

Figure 1 is a diagrammatic top plan view of a well derrick illustrating a rotary drawworks as embodying this invention as positioned therein.

Figure 2 is a side elevation partly in vertical mid-section of a rotary drawworks embodying this invention.

Figure 3 is an end elevation thereof, illustrating the low speed sprocket as broken away to illustrate the forged brake rim construction and brake bands mounted thereon.

Figure 4 is an isometric view of a forged rolled brake rim embodied in this invention.

Figure 5 is a fragmental sectional front elevation illustrating the third speed clutch mechanism embodied in this invention as illustrating the same as mounted upon a fragment of the drum shaft.

Figure 6 is an end elevation thereof, taken substantially on the line 6-6 of Figure 5.

Figure 7 is a fragmental sectional view illustrating the clutch faces of the third speed clutch mechanism illustrated in Figure 5.

Figure 8 is a fragmental side elevation of the rotary drum construction embodied in this invention, illustrating the cable securing means for securing the line cable to the said drum.

Figure 9 is a fragmental end elevation of the cable securing means illustrated in Figure 8.

Figure 10 is a detached fragmental view

of a brake band construction embodied in this invention and illustrating the brake securing means as provided for securing the dead end of the brake bands embodied in this invention.

Figure 11 is a fragmental top plan view illustrating the unitary control supporting mechanism for the controls for the clutch means for each of the three speed clutches of the rotary drawworks embodied in this invention.

In the preferred embodiment of this invention, illustrated in the accompanying drawings, 1 illustrates the floor of the well derrick.

15 Mounted in the floor derrick is a rotary drilling machine 2 which is operated for the purpose of rotating the rotary drill stem (not shown), to the end of which the drilling bit (likewise not shown) is secured for drilling

20 the hole in the ground to the depth required or desired. The rotary drill stem is supported upon a hydraulic swivel which is likewise not shown but which is well understood in the art from or by a cable which passes over the 25 crown block of the derrick and is wound upon the drum 3 of the rotary drawworks 4 which is mounted upon the derrick floor 1 in substantially the position illustrated in Figure 1.

It is essential that the drawworks 4 be as 30 compact as possible, that is, that the distance between the outer posts 5 and 6 thereof be maintained at a minimum so that the rotary drive sprocket 6^a, which is carried upon the line shaft 7 of the rotary drawworks 4, will

35 align with the drive sprocket 8 of the rotary drilling machine or apparatus 2, and also so that the catheads 9 of the rotary drawworks 4 will not be extended too far from alignment with the table 10 of the rotary

40 machine 2, as the catheads 9 are employed with a cat line in a manner well understood in the art for operating the tongs and like devices as used for the screwing up and unscrewing of the drill stem sections and for 45 like purposes during the rotary process of drilling.

It is also essential in a rotary drawworks that the line drum 3 thereof be in position so as to maintain the cable 11 thereof in approximate alignment with the crown block sheave over which the same is passed.

In the drilling of deep wells, particularly wells of five thousand depth or over, it is particularly desirable that the drum 3 be 55 not only of increased length between the flanges thereof, but that the diameter of the spool of the drum 3 be large so as to prevent variation of the speed of travel of the line 11 which is wound thereon as the said line is coiled upon the said spool. The increasing depth of wells of course necessitates the provision of increased drum area for winding of the line cable and this increased demand for length of the drum 3 must not require an 60 increased spreading of the posts 5 and 6 of

the drawworks 4. In order to permit wide variation of operation of the rotary drawworks, according to the conditions met during the drilling of the well, it is preferable that the drawworks be provided with considerable speed variation for driving the drum 3. For this purpose, the drawworks is provided with three speeds, any one of which may be operated to drive the drum 3. The line shaft 7 of the rotary drawworks 4 is driven by means of a motor or engine 12 which is positioned exterior of the derrick 1 and is connected through a chain drive with a sprocket 13 which is rigidly secured to the line shaft 7.

The line shaft 7 is journaled in bearings which are secured to the end posts 5 and 6 and the third post 14 of the drawworks 4.

70 The rotary drive sprocket 6^a is loosely journaled upon the shaft 7 and is preferably provided with a jaw-clutch 15 for releasably

engaging the sprocket 6^a with the line shaft 7 when it is desired to operate the rotary machine 2, and which sprocket 6^a may be disengaged from the line shaft 7 when it is

desired to operate the rotary drum 3 for hoisting or lowering the drill stem into the well hole being formed. The jaw-clutch 15 may be of any desired or preferred construction and is herein illustrated as comprising

55 a clutch collar 16 which is slidably keyed to the shaft 7 so as to permit longitudinal movement of the collar 16 on the shaft 7 and so as to prevent rotation of the collar 16 relative to the shaft 7 so that the jaw engaging

face 17 of the clutch collar 16 may be moved into engagement with the jaw-clutch engaging face 18 which is preferably formed integral with the hub of the sprocket 6^a. The

collar 16 has an annular groove formed there- 105 in into which pins carried by the fork 19 extend for sliding the collar 16 on the said shaft 7. The fork 19 is pivotally supported by means of a bracket 20, which bracket 20

is secured to the beam 21 which connects the posts 5, 6 and 14 of the drawworks at their upper end. An actuating rod 22 is secured to the fork 19 at a pin 23 and is secured to an actuating lever 24 at its opposite end at a pin 25.

110 A pawl and ratchet latch means 26 are provided for latching the clutch collar 16 into driving engagement with the sprocket 6^a and the pawl and ratchet means and actuating lever 24 are positioned at the left of the drawworks as illustrated in Figure

120 3 so as to permit easy access of the operator of the drawworks from such position. Keyed to the line shaft 7 is a low speed sprocket 27, an intermediate speed sprocket 28 and a high or third speed sprocket 29.

125 Mounted below the line shaft 7 and in bearings 30 is the drum shaft 31, upon which drum shaft 31 low, intermediate and third speed sprockets 32, 33 and 34 are journaled, each of which sprockets is provided with

clutch means for releasably engaging the same with the drum shaft 31 as will herein-after be described. The drum 3 is keyed to the drum shaft 31 and is preferably constructed of a spool 35, which spool 35 is preferably constructed of a cylindrical portion 36 which has at its opposite end downwardly inclined integral flanges 37 which are formed integral with the oppositely extending hubs 38 which are keyed to the portions 39 of increased diameter of the drum shaft 31. A plurality of webs 40 are cast integral with the cylindrical portion 36 of the drum 3 for removing the same. Formed integral with and at opposite ends of the spool 35 are outwardly extending annular flanges 41.

Forged rolled brake rims 42 are provided and which forged rolled brake rims are preferably composed of a single portion of steel forged while hot in a manner similar to the forging of rims for machine car wheels and the like and during the forging are rolled at their outer edge with a downwardly extending flange 43 which provides a cooling solution retaining rim for maintaining a cooling solution within the brake rim for cooling the same during braking operations. The outer edge of the rim 42 is also formed with an upwardly extending flange 44 which provides a retaining rim for retaining the brake band 45 against lateral movement upon the rim 42. The brake rim 44 provides a braking surface 46 which is preferably hardened by any of the well known processes and the rim 42 is formed at its inner end with an inwardly extending annular flange 47, which annular flange 47 provides an edge shoulder 48 which fits the edge shoulder 49 formed by the annular abutment 50 which is formed integral with the flanges 41 of the spool 35. Rivets 51 are countersunk in the flanges 41 and extend through the annular flange 47 and are riveted over within the brake rims 42 so that a substantially flat surface is maintained at the interior of the spool flanges 41. The annular flange 47 of the brake rim 42 is cut away at a plurality of points as illustrated at 52 so as to accommodate keys 53 which fit within the cut away recesses 52 which are secured to the flanges 41 at the increased portions 54 of the annular abutments 50 formed on the outer surface of the flanges 41. The keys 53 are preferably secured to the flanges 41 by means of countersunk rivets 55. The rivets 51 and 55 are preferably cold pressed into position by means of a jack interposed between the flanges 41 and their inner ends are then heated by means of an acetylene torch or the like and riveted over by the use of a hydraulic riveting machine.

We have discovered that the provision of forged rolled brake rims enables us to embody in the construction of our rotary draw works drum brake rims which have chemical and physical characteristics which are best suited

to the conditions of service, insuring greater strength, longer wearing and the ability to afford maximum smooth braking operation, due to the ability to provide such forged and rolled brake rims of a grade of metal which is most suited for its production which is not limited to the use of low carbon steel and in the case where such brake rims are pressed by the material most suited for such brake rim construction, may be employed so as to insure the highest maximum brake contact as well as brake power at all possible positions of the brake wheel with additional safety, due to the increased and wearing qualities of any other type of brake rims now on the market and which includes not only the features of additional stiffness but enables us to produce a brake rim which has an absolutely true rim and braking surface, whereby jerkiness of control may be avoided.

The hub 38 at the left-hand end of the spool 35 is formed so as to extend into the interior of the forged brake rim 42 and of sufficient length or extent to provide a firm bearing support for the drum 3 at that end and extends into the drum 42 so as to engage the end face 56 of the low speed sprocket 32 upon the drum shaft 31. In order to accommodate for the clutch 57 for the third speed sprocket 34, the hub 38 formed at the right end of the spool 35 extends inwardly into the interior of the cylindrical portion 36 of the spool 35 and extends only slightly into the interior of the right hand rim 42 and is of sufficient extent to provide a firm bearing support at this end of the drum 3. This hub 38 at the right hand end of the spool 35 extends inwardly into position as before described so as to permit the mounting of the clutch collar 58 on the line shaft 31 for releasably securing the third speed sprocket 34 to the shaft 31.

The flanges 42 are formed with a plurality of webs 59 which extend outwardly from the hub 38 thereof to the annular abutment 50 and are for the purpose of reinforcing the flanges 41. Cast integral with the flanges 41 is a cable race 60 into which the cable 11 is extended through a bore 61 formed preferably at the right hand flange 41 and a clamp 62 is secured to the end of the cable 11 in position to engage the end of the race 60 so as to securely fasten the cable 11 to the drum 3.

The clutch means provided for reasonably clutching the third speed sprocket 34 to the drum shaft 31 is preferably composed of a clutch collar 58 which is keyed to the shaft 31 so as to be longitudinally slidable thereon and is provided at its end engaging face with a cylindrical cut away recess 63 which has formed on its inner face 64 a plurality of clutch projections 65 which are adapted to engage the clutch segments 66 which are formed integral with the hub 67 of the third speed sprocket 34, which third speed sprocket 34 is loosely journaled upon the shaft 31 and

is maintained against endwise motion at its outer end by engagement with the end of the bearing 30 which is secured to the third post 14 of the drawworks and in which the shaft 31 is journaled. The collar 58 has an annular recess 68 formed therein into which pins 69, carried by the fork 70, project for sliding the clutch collar 58 longitudinally along the shaft 31. The fork 70 is pivotally secured to a bracket 71 at a pin 72 and which bracket 71 is secured to the third post 14 of the drawworks. The engaging clutch segments 65 and 66 of the collar 58, and sprocket 34, respectively, are formed with 15 tapered engaging edges 73, as illustrated in Figure 7.

Clutch collars 74 and 75 having tapered engaging faces 76 and 77 are keyed to the drum shaft 31 in position to engage the 20 tapered engaging faces 78 and 79 of the low and second speed sprockets 32 and 33, respectively. The clutch actuating yokes 80 and 81 for these aforesaid clutch collars are pivotally supported by means of brackets 82 and 83, respectively, which are secured to the respective posts 5 and 14 of the drawworks. The yokes 80 and 81 are pivotally secured at pins 84 and 85, respectively, to actuating rods 86 and 86^a which extend longitudinally of the drawworks to the left hand end thereof. The fork 70 for the third speed clutch collar 58 is rigidly secured to a curved actuating lever 87 and the curved actuating lever 87 is secured to the floor 1 of the derrick by means of a bracket similar to the bracket 84 and is secured to an actuating rod 88 which likewise extends longitudinally of the drawworks to the left end thereof.

The actuating rods 86 and 88 are secured 40 to downwardly extending projections which are formed integral with the collars 89 which are mounted upon a shaft 90 which is supported in a bracket 91 secured to the derrick floor. The collars 90 at their opposite faces have arms 92 formed integral therewith so that the collars 89 with the arms 92 and the downwardly projecting arm which connects with the actuating rods 86 and 88 form bearing crank levers which are secured 45 at their inner ends at pins 93 which are passed through ears 94 formed integral with foot actuating pedals 95 so that as the foot actuating pedals 95 are depressed, the rods 86 and 88 will be actuated to engage or disengage the respective clutches for the shaft 2 or third speed of the rotary drawworks as desired by the operator.

As illustrated, the pedal 96 is the first speed control, the pedal 97 is the second speed control and the intermediate pedal 98 the third speed control. The pedals at their opposite ends are formed with hubs 99 which are journaled upon a pin 100 mounted in a bracket 101 which is secured to the floor 1 of the derrick. This manner of bringing on the

speed controls to a common point and permitting their actuation by means of the feet of the operator is an important feature of this invention as it enables a more easy, safe and accurate control of the drawworks and so centralizes the controls.

The brake bands 45 which are mounted upon the brake rims 42 are preferably constructed of a band 102, to which band 102 the brake lining 103 is secured by means of countersunk bolts or rivets 104 which are countersunk in the brake lining 103 and extend through the brake band 102. The brake lining 103 is sawed at a plurality of points 105 so as to enable the same to more accurately follow the contour of the brake rims 42. Any suitable or desirable form of brake actuating means 106, as is well understood in the art, may be provided for actuating the brake bands 45 and the live end 107 of the brake band 45 is secured to this brake actuating means 106 in any desired or preferred manner. The dead end 108 of the brake bands 45 is secured to an eye bolt 109 in any desired or preferred manner as illustrated at 110 and extends through the floor 1 of the derrick through a bracket 111 which is secured to the floor 1 and within which a collar 112 is mounted, and which collar 112 is screw-threaded to the end of the eye bolt 109 so as to 95 adjustably and firmly secure the dead end 108 of the brake bands 45. Lock means are provided for locking the collar 112 in the adjusted position, and which lock means preferably comprises a lock link 113 which is pivotally secured at a pin 114 supported by the bracket 111 and which lock link 113 has a locking recess 115 formed at its engaging end of substantially the shape to engage the hexagonal head 116 of the collar 112 so as to 100 prevent rotation of the collar 112 on the eye bolt 109.

Means are provided for supporting the brake bands 45 so that the same will not drag upon the brake rims 42 when not in use, 110 which means preferably comprise a cable 117 which is secured to a turn buckle 118, and which turn buckle 118 is at its opposite end secured to the beam 21 of the rotary drawworks. The cable 117 passes through a clip 119 secured to the rear face of the brake band 102 and extends around the brake band 102 and is secured to the derrick floor at 120 so as to support and hold up the brake band 45 when it is not desired to operate the same. The turn buckle 118 permits accurate adjustment of this holding means so as to adjust the non-operating position of the brake band 45.

Having fully described a preferred embodiment of our invention, it is to be understood that we do not wish to be limited to the exact details herein set forth which may obviously be varied without departing from the 125

spirit of our invention as set forth in the appended claim.

We claim:

In combination with a rotary draw works,
5 a drum comprising a spool having outwardly extending flanges formed integral therewith, oppositely extending hubs formed integral with the said spool, one of which hubs extends into the interior of the spool and the
10 other of which hub extends outward from the said spool, and forged rolled brake rims secured to the said flanges.

Signed at Torrance, Calif., this 10th day of June, 1926.
